ATTORNEY.

UNITED STATES PATENT OFFICE.

CHARLES C. JORDAN, OF BALTIMORE, MARYLAND.

WASHBOILER.

SPECIFICATION forming part of Letters Patent No. 643,378, dated February 13, 1900.

Application filed October 30, 1899. Serial No. 735,149. (No model.)

To all whom it may concern:

Be it known that I, CHARLES C. JORDAN, a citizen of the United States, residing at Baltimore, in the State of Maryland, have invented 5 certain new and useful Improvements in Washboilers, of which the following is a specification.

This invention relates to improvements in washboilers wherein means are employed for 10 the circulation of the hot water and steam.

The invention consists of the novel arrangement and combination of parts, as hereinafter described and claimed.

Referring to the drawings, Figure 1 is a 15 vertical longitudinal section through a boiler and shows my improved construction and removable bottom, which latter is sectioned on the line 1 1 of Fig. 2. Fig. 2 is a bottom plan view of the removable bottom and illustrates 20 the same as divided into compartments. Fig. 3 is a top plan view of a portion of a boiler with the cover removed and showing the removable bottom therein.

In the drawings, A designates an ordinary 25 sheet-metal boiler and is provided with the usual cover b. A removable bottom C is placed within the boiler and rests on the bottom of the latter, and said removable bottom is provided with a downward - projecting 30 flange c, which extends entirely around the same. Partition-walls d extend across the under surface of the removable bottom and connect with the downward-projecting flange c, thereby forming on said under surface four 35 compartments e. Short pipes f project upward from the top of the removable bottom, and one of said pipes opens into each compartment e. To permit the water and steam to circulate into the compartments, the flange 40 c is provided with holes or notches g, which open from the boiler proper into each compartment.

The vertical wall of the boiler A is provided at intervals on its internal surface with 45 keepers h, which are secured thereto by any suitable means. Short vertical pipes i are loosely supported, each by two of the keepers h, against the vertical wall of the boiler, and each vertical pipe at its top carries a 50 short lateral pipe h', which serves as a discharge-nozzle. At its lower end each vertical pipe i is provided with a double elbow k, which latter is adapted to be swung out or 55 away from the wall of the boiler and take position over the removable bottom, as in Fig.

1, and also connect with one of the short pipes f, projecting upward. The vertical pipe, nozzle, and double elbow may be raised and lowered vertically to connect with or disconnect from the short pipe f. A handle l is secured 60 to the removable bottom for convenience in lifting the latter out of the boiler.

The operation is simple and as follows: When the removable bottom C has been placed within the boiler and the several elbows k connected with the pipes f, the device 65 is ready for use. Water and steam from each of the compartments e will be forced up through the short pipes f, thence through the elbows k, up the pipes i, and finally discharge 70 at the nozzle h' onto the contents of the boiler.

When it is desired to remove the bottom C from the boiler, the several pipes i will be drawn up through the keepers h until the elbows are each disconnected from the short 75 pipes f. The elbows are then swung around against the vertical wall of the boiler, as in Fig. 3, and the removable bottom C may then be lifted out, leaving the pipes attached to the walls of the boiler.

Having thus described my invention, what I claim as new, and desire to secure by Letters Patent, is—

1. The combination of a receptacle; a removable bottom in said receptacle—said bottom provided with a plural number of compartments each in communication with the receptacle and having a pipe opening into each compartment and projecting upward; and upward - projecting discharge - pipes loosely 85 attached to the walls of the receptacle and having double elbows for connection with the pipes opening into the compartments and adapted to be swung around against the sides of the boiler when not in use.

2. The combination of a receptacle; a removable bottom in said receptacle and provided with compartments in communication with the receptacle; keepers on the wall of the receptacle; a pipe loosely supported by said 100 keepers and having a double elbow, said pipe and elbow capable of both a horizontal and vertical movement, as set forth.

In testimony whereof I affix my signature in the presence of two witnesses.

CHARLES C. JORDAN.
